SEWING MACHINE

Norman V. Christensen, Chicago, Ill., assignor to
Union Special Machine Company, Chicago, Ill.,
a corporation of Illinois

Application August 5, 1941, Serial No. 405,539

4 Claims. (Cl. 112—258)

This invention relates to sewing machines and more particularly to an improved and simplified construction and arrangement of the parts of such machines. The present case is a continuation-in-part of my pending application Ser. No. 306,826, filed November 30, 1939, now Patent No. 2,294,074, granted August 25, 1942 and is directed to a divisible portion of the disclosure thereof.

A feature of the invention is the formation of a number of independent units or assemblies, each with its own frame structure, a plurality of the units being readily connected to form a complete machine. In a preferred form of the invention, certain of the units are adapted for interchangeable connection with another, so that machines of different types or intended for different purposes may be produced by coupling together appropriately selected units. This not only simplifies the assembly of individual machines, due to their unit construction, but also enables large-scale production of the several units. A unit capable of employment in a number of different styles of machines may be produced in relatively large quantities, thus reducing the cost of the unit.

In the preferred application of the invention, a feed-off-the-arm type of machine may be formed in two separate units,—a base unit and an upper arm unit, the latter having a vertical standard at one end adapted to be readily connected with or disconnected from the base unit. The arrangement is such that the driving connections between the two units are completely coupled upon merely connecting together the frames of the units. Moreover, the upper arm unit, with its standard, is such that it may be used interchangeably with the feed-off-the-arm base unit or with a flat bed unit by simply attaching the standard to the frame of the selected base. Other base units may likewise be used interchangeably with the same upper arm unit. So also, a single base unit may, if desired, be adapted for interchangeable use with different upper arm units.

Due to the simplicity of the connection and disconnection of the several units, a single upper arm, for example, may be provided with several base units, which may be used, as desired, for the performance of different types of work. But a primary advantage of the interchangeability of the units is that the production of different types of machines may be simplified and their cost reduced to a minimum.

Various novel constructions and arrangements are embodied in the several units forming part

of the present invention. The feed-off-the-arm base unit, for example, when coupled with the upper arm unit combines the advantages of a number of prior feed-off-the-arm machines. It is simple in construction, easy to assemble, convenient to operate and capable of operation at high speed. Toward these ends the work arm of this base unit has only two sides which are at substantially a right angle to each other and are disposed substantially horizontally. In conjunction with the upper arm, the work arm practically presents, in plan, the configuration of a right-angled triangle.

In general, it has been an object of the invention to so construct the several units that each is relatively small and compact, utilizes rotary motion to the greatest extent possible, may be operated at high speeds with a minimum of vibration, and may be quickly started and stopped without injury to the mechanism.

Another object of the invention has been to avoid, as far as possible, the provision of internal projections on the machine. This has been accomplished through the provision of a frame, the outer surfaces of which are well rounded and smooth and which affords, at its interior, a series of chambers or cavities for the accommodation not only of the stitch forming, feed, and driving mechanisms, but also of the thread tensions and mechanism for lifting the presser element and means for controlling the tensions for the needle and looper threads.

Still another object of the invention is to provide within a hollow frame, of the character above specified, isolated chambers in which the needle mechanism, the feed mechanism, the drive mechanism and other driven parts of the machine are separately housed, said chambers having separate oil supply provisions for automatic lubrication of the several mechanisms. Other objects and attendant advantages will appear from a detailed description of an illustrative form of the invention which will now be given in conjunction with the accompanying drawings, in which:

Figure I is a plan view of a complete sewing machine of the feed-off-the-arm type, a portion of the frame or housing of the upper unit being broken out at the top to expose a part of the interior.

Figure II is a view partly in front elevation and partly in vertical section, taken along the line II—II in the direction of the arrows of Figure I.

Figure III is a horizontal, sectional view through the base and work supporting arm of

the lower unit of the machine, taken along the line III—III of Figure II in the direction of the arrows in Figure II.

Figures IV, V, VI, VII and VIII are vertical sectional views, taken transversely at intervals along the work supporting arm, at the points indicated, respectively, by the lines and arrows IV—IV, V—V, VI—VI, VII—VII and VIII—VIII in Figures III, IX and X.

Figure IX is a detailed view showing in section, along the line IX—IX and in the direction of the arrows in Figure III, the anchorage portion of the work arm.

Figure X is a vertical sectional view through the free end of the work arm along the line X—X of Figure III and taken in the direction indicated by the arrows, the lower portion of the needle head and associated devices being disclosed in elevation.

Figure XI is a front elevation of the needle head of the machine with its cover plate removed to expose the interior of the mechanism.

Figure XII is a side elevation of a portion of the work supporting arm of the lower unit of the machine, a portion of the frame or housing being broken away to expose the thread tensioning mechanism.

Figure XIII is a plan view of the upper unit of the machine, with a portion broken away to show the presser foot lifting mechanism and with a part adjacent the right end omitted.

Figure XIV is a transverse, sectional view through the overhanging arm taken along the line XIV—XIV of Figure I in the direction of the arrows.

Figure XV is a perspective view showing the two units of the machine in spaced position prior to assembly.

Figure XVI is a view, partly in side elevation and partly in section along the line XVI—XVI of Figure XVII, showing an upper unit of the type disclosed in Figures I to XV, inclusive, applied to a different base unit, i. e., that of a flat bed machine.

Figure XVII is a horizontal, sectional view along the line XVII—XVII of Figure XVI through the flat bed base unit, and

Figure XVIII is a perspective view of the entire flat bed base unit.

Referring now to Figures XV and XVIII, there is disclosed an upper unit A comprising a vertical standard portion and a horizontally extending upper arm portion, which will be described hereinafter in greater detail. Beneath the upper unit in Figure XV there is shown a feed-off-the-arm unit B adapted to be connected with the upper unit to form a complete machine. As will be explained in greater detail hereinafter, the coupling of the two units A and B requires simply the placing of the upper unit in correct position on the lower unit and securing these units together by means of appropriate screws or bolts. The only driving or operating connection between the two units is the gearing indicated in Figure XV, which will be hereinafter more fully described.

The upper unit A is also adapted to be combined with a base unit C (Figure XVIII) to form a complete flat bed type of machine. Here again, the connection of the two units A and C requires simply the proper application of one to the other and the insertion and tightening of a series of bolts or screws. The driving or operating connection between the two units is accomplished entirely through the gearing indicated.

Turning now to Figures I to XV, inclusive, the construction of the feed-off-the-arm machine, produced by combining units A and B, will be described. Referring particularly to Figure I, the improved machine has a frame which comprises a base portion 1 of the lower unit, which is of substantially rectangular configuration and from which extends, horizontally at an angle, an anchorage portion 2 of a work arm 3, the free end 4 of which is disposed at substantially a right angle to the anchorage portion 2 and lies in the same horizontal plane with the latter.

From Figures II and III, it will be observed that the base portion 1 has a chamber 5 and that the work arm 3 is also hollow and has the connecting end of its anchorage portion 2 in direct communication with the chamber in the base. Rising from the base portion 1 and secured thereto by screws or bolts 6 is a vertical standard 6 which is hollow and communicates openly with the chamber 5 of said base portion, said standard forming part of the upper unit and supporting a horizontal, overhanging arm 7 which terminates in a needle head 8. As viewed in Figure I, the overhanging arm 7 forms a triangle with the portions 2 and 4 of the work arm 3 and has the needle head at its outer end directly above the free end of the terminal portion 4 of said work arm. The screws 6 are passed upwardly through passages in the base portion, and have threaded engagement with openings in a flange at the bottom of the standard 6. This forms the only connection to be made or undone between the two units A and B.

For operation of the machine, a combined hand wheel and belt pulley 11 is provided; and beneath the pulley element the base portion 1 is slotted, as indicated at 12, for passage of a conventional driving belt. The combined hand wheel and belt pulley 11 is affixed to a driving shaft 13 which extends longitudinally of the overhanging arm 7, and which is journaled in suitable bearings 14, 15 and 16. At its distal end (Figures II and XI), the driving shaft 13 enters the needle head 8 and drives a crank disc 17 carrying a crank pin 18. By means of a link 19, the crank pin 18 is connected to a pin 21 forming an integral part of a clamp collar 22 carried by the needle bar 23. The free end of the pin 21 extends beyond the end of the link 19 and is formed with flattened sides which engage guide plates 24 secured to the inner face of the needle head by screws 25, thus resisting any torsional forces exerted by the link 19. The needle bar 23 is mounted for reciprocation in suitable bearing bushings 26 in the needle head 8 and at its lower end carries one or more needles 27 (three such needles being shown in the illustrated example, Figure X) which cooperate with complementary stitch forming mechanism situated in the free end of the work arm to effect the formation of stitches.

As best illustrated in Figure II, the bearing bushings 15, 16 are mounted in cross walls 28, 29 in the overhanging arm 7 which serve to divide that arm into three compartments, namely, a needle head compartment 31, a gear compartment 32 within the hollow standard 6, and an intermediate compartment 33 in which suitable needle thread tensions 34 are mounted on a bracket plate 35 secured by screws 36. Access to the intermediate compartment 33 is had through a cover plate 37 mounted by hinges 38 on the overhanging arm of the machine. As shown in Figure I, the needle threads *n* pass from a source

of supply through eyelets 39, mounted in the rear wall of the overhanging arm, thence through the tension devices 34, and through eyelets 41 in the front wall of the overhanging arm, and ultimately through suitable guides and take-up members 42, 43 and 44 to the needles 27.

Secured in the lower portion of the needle head 8 by a set screw 45 (Figure XI) is a depending bar 46 on which is mounted a collar 47 (Figures II and X) rigidly secured thereto. The collar 47 is provided with laterally extending lugs 48, 49 in which a presser bar 51, carrying at its lower end a presser foot 52, is mounted for vertical movement. The presser bar 51 adjacent the presser foot 52 is provided with a laterally extending tongue member 53 which engages a slot 54 formed in the lower end of the depending bar 46, thus resisting any tendency of the presser bar 51 and presser foot 52 to turn about the axis of the presser bar. At its upper end the collar 47 is further provided with a rearwardly extending arm 55, which at its outer end has a notch 56 accommodating one end of a leaf spring 57. The leaf spring 57 at its other end engages the end of the presser bar 51 and through an adjustable screw 58 tends to urge the presser foot into yielding engagement with the work on the work arm 3. By means of the screw 58, the pressure exerted by the spring 57 on the presser bar 51 and presser foot 52 may be varied. Between the guiding lugs 48, 49 the presser bar 51 carries a shoulder screw 59 which, through a flexible member 61, is connected with a crank arm 62 (Figures XI and XIII), affixed to a rock shaft 63 journaled in bearings 64, 65 in the overhanging arm of the machine. The endwise movement of this rock shaft 63 is prevented by engagement of the opposite ends of the bearing 64 by the hub of the arm 62 and a thrust collar 66. Adjacent the bearing 65 the rock shaft 63 carries a collar 67 clamped thereto and having a laterally projecting crank arm 68, extending through a clearance opening in the wall of the overhanging arm of the machine, the free end of which is adapted to be engaged by a chain or other suitable means leading to a foot treadle or the like for rocking the shaft and thereby lifting the presser foot 52 from contact with the work on the work support. The collar 67 is further provided with a laterally projecting lug 69 which extends beneath the tension devices 34 and upon rocking of the shaft 63 to lift the presser foot 52, this lug 69 will engage the release pins 71 of the tension members 34, and separate the tension discs 70 (see Figures II, XIII and XIV). From Figure II, it is to be particularly noted that the flexible connecting member 61 extends through a tube 60 within the hollow of the head 8, the top of said tube being well above the level of an oil supply (conventionally indicated) at the bottom of said head and out of the range of oil splashed by the moving parts of the needle actuating mechanism.

Within the hollow standard 6, the driving shaft 13 carries a pinion 72 which meshes with an idler gear 73 journaled for rotation on a stationary shaft 14, and the idler gear 73 in turn meshes with a second pinion 75, identical to the pinion 72 mounted on a short countershaft 76 journaled in bearings 77, 78 in the upstanding portion 79 of the base 1. The chamber 5 in this portion of the base is closed at the bottom by a cover plate 81 and gasket 82, thus providing, in conjunction with the hollow standard, an oil-tight compartment in which the above-mentioned gears operate. As will be seen the gear 75 dips into the

lubricant in the compartment or reservoir mentioned and, therefore, when operated, serves to throw a fine spray of the lubricant into the standard to lubricate the various surfaces requiring it. A part of the lubricant will be collected in the reservoir 75a at the lower end of the standard and from this will be delivered through the passage 75b to the bearing 77 and will then be returned to the compartment. The gears 73 and 75 form the only driving connection between the upper and lower units so that these are automatically coupled for operation upon simply securing the frames of the two units together.

With particular reference to Figures III, IX and X, wherein the mechanism within the work supporting arm 3 may be viewed in detail, it will be observed that the shaft 76 in addition to the gear 75 carries a bevel gear 83 which meshes with an identical bevel gear 84 affixed to one end of a transmission shaft 85 journaled in bearing bushings 86, 87 and 88, supported, respectively by an interiorly projecting lug 89, a cross wall 91 and an end wall 92 of the work supporting arm 3.

The connection from the shaft 85 for operating the complementary stitch forming devices and feed dog in the work arm and the particular form of these devices may be varied, as desired, but a construction and arrangement which is especially desirable for these purposes is disclosed herein and is disclosed and claimed in the application of Clarence C. Smith, Ser. No. 323,528, filed March 12, 1940.

At the free end of the work arm 3 in a compartment 93 are located one or more loopers 94, which constitute the complementary stitch forming means previously referred to (three such loopers being shown in the illustrated example). As shown, the loopers 94 are mounted in a holder 95 secured to the end of a looper shaft 96, which is journaled for oscillation and endwise reciprocation in bearings 97, 98 and 99 interiorly of the free end portion 4 of the work arm 3. Intermediate the bearings 98 and 99, the looper shaft 96 carries an arm 101 clamped thereto, which arm at its outer end is connected by means of a link 102 to one end of a lever 103 for oscillation on a cross pin 104 carried by suitable formations in the interior of the work arm 3. The other end of the bell crank lever 103 is connected by a pitman 105 with a crank or eccentric member 106 on the shaft 85, located adjacent the bushing 87. Through the above described train of mechanism, the shaft 96 will be oscillated to give the loopers their taking and loop shedding movements.

Freely mounted on the looper shaft 96 is a collar 107 which is held against endwise movement by thrust collars 108. The collar 107 is provided with a laterally projecting stud 109 which is engaged by one end of a strap link 111, the other end of which embraces an eccentric 112 on the shaft 85. As the shaft 85 is rotated, the eccentric 112, through this train of mechanism, will induce endwise reciprocation of the looper shaft, and thus impart to the loopers 94 their needle-avoiding movement. The collar 107 is further provided with a depending lug 113, the flattened sides of which engage guide blocks 114 secured by means of screws 116 to a boss 115 rising from the interior of the work arm. This guiding arrangement serves to absorb any torsion imparted to the collar 107 by the link 111.

Secured to the forward end of the work arm 3 is a throat plate 117 having needle holes and feed dog slots 118 through which the sections of a

75 four-motion feed dog 119 operate to engage the

fabrics in the usual manner. The feed dog 119 is provided with a depending shank 121 secured by means of a screw 122 to the forward end of a feed bar 123. The feed bar 123 extends lengthwise of the work supporting end of the arm 3 and intermediate its ends is pivotally supported by the upper end of a vertical frame 124, which at its lower end is mounted for oscillation about a cross pin 125 mounted in suitable bosses 126 on the interior of the work arm. At its rear end the feed bar 123 is provided with a longitudinal bore 127 in which a rod 128 is engaged for sliding reciprocation. This rod 128 is formed as an integral part of an eccentric strap 129 embracing an eccentric 131 on the shaft 85. As the shaft 85 revolves, the feed bar 123 will not be affected by the endwise components of motion of the rod 128, but the vertical component of its motion will cause the feed bar to oscillate about its pivotal support on the frame 124 and thus impart a rising and falling movement to the feed dog 119.

Pivotedly connected to the feed bar 123 adjacent its pivotal support is a link 132, the other end of which is pivotally connected by a stud 133 in an arcuate slot 134 formed in a rock member 135 which at its lower end is pivotally mounted on a cross pin 136 secured in suitable lugs 137 projecting interiorly of the work arm 3. Pivotally connected to the rock member 135 is one end of a pitman 138, the other end of which embraces an eccentric 139 on the shaft 85. Rotation of the shaft 85 will impart oscillation to the rock member 135, and through the link 132 these oscillations will be converted into reciprocating movement in the feed bar for its feed and return stroke. By adjusting the rear end of the link 132 along the slot 134, the length of the feed stroke can be varied.

The looper thread or threads 1 are led from a source of supply into a slot 141 formed in the outer wall of the anchorage portion 2 of the work arm 3, and through this slot are led into a thread tension recess or cavity 142 formed in the rear side of the work arm. This recess or cavity 142 contains thread tension devices 143, and access thereto for the purpose of threading is had through a retractable cover plate 144 hinged to the side wall of the work arm at 145. After passing through the thread tension devices 143, the looper thread is led through a slot 146 formed in the upper rear wall of the work arm, and thence into a housing 147 at the elbow of the work arm formed by a hinged cover 148, and in the housing 147 there is located a suitable take-up device comprising a rotary cam 149 carried by the end of the shaft 85 and suitable thread guiding means including a slotted plate 151 secured to the end wall of the work arm by a screw 152 and slotted stripper blade 153, together with suitable thread guiding means including a pin 154 and thread guides 155. From the take-up devices the thread 1 is led through a groove 156 formed in the upper edge of the side wall of the work arm 3 to the loopers 84. With particular reference to Figure III, the above described course of the looper threads 1 is indicated by dot-and-dash lines.

The entire work arm 3, including its anchorage portion 2, is closed at the top by a correspondingly configured cover plate 157 secured thereon by screws 158, as most clearly indicated in Figure I. Between the work arm 3 and the cover plate 157, there is a gasket 159, which encloses the mechanism within the work arm in an oil-tight casing containing an oil bath. The 75

cover plate 157 extends lengthwise of the free end 4 of the work arm 3 beyond its point of attachment by the screws 158 and also extends along the anchorage portion 2 of the work arm beyond its point of attachment, and along this edge it is spaced to some extent from the edge of the work arm wall to provide an opening or slot 161 into which the thread 1 may be led to guide it into the thread guiding slots 141, 146 and 156.

As may be seen from the drawings, the mechanism of the machine is enclosed in three oil-tight compartments or chambers in each of which a quantity of oil is encased for splash lubrication applied to the mechanism situated therein. These compartments are the needle head compartment 31 in which the parts are lubricated as already explained, the gear compartment 32 within the standard 6, which at its lower end extends laterally to the cross wall 91 in the work arm 3, and a compartment 160 extending along the work arm from the cross wall 91 to the cross wall 97 at the free end of the work arm 3. As a consequence of this arrangement, different grades of oil may be employed for the three different mechanisms above referred to. Not only is a gasket employed to secure the cover plate 157 for the work arm including its anchorage portion, but an additional gasket 160 is also located between the cooperating upper and lower units A and B which are held together by screws, as explained.

For access to the loopers for inspection and threading, the work arm is provided at its free end with side openings, which are closed by covers 162 hinged at 163 and provided at their hinged point with cam surfaces 164 (Figure VIII) which engage the arms of a leaf spring 165 secured to the work arm 3 by a screw 166 and operating to hold the covers either in open or closed position.

From the above description, it will be particularly observed that the driving mechanism of the feed-off-the-arm sewing machine, produced by combining units A and B, comprises gear-connected shafts which extend from the standard 6 through the overhanging arm 7 and from the standard through the anchorage portion 2 of the work arm 3. Power is transmitted to points relatively remote from the standard by rotary elements exclusively. For imparting the desired movements (reciprocatory or oscillatory) to the needle bar 23, the loopers 84 and the feed dog 119, additional actuating mechanism, driven by said gear-connected shafts, is provided, which additional mechanism is confined to the needle head compartment 31 and the compartment 160 extending throughout the free end of the work arm 3. Thus, this invention materially reduces, from the standpoint of size and weight, the moving parts required for imparting such special movements to the stitch forming and feeding mechanism, permitting high speed operation, and at the same time resulting in obvious simplification, economy, and avoidance of vibration with respect to the entire driving mechanism. Moreover, the advantages of the co-planar type of work supporting arm are also obtained.

It will also be observed that numerous other advantages are gained, including especially an efficient system of lubrication for the moving parts most subject to wear, a convenient method of conducting the looper threads around an angular work supporting arm, and other advantages which follow from the particular design

of the work supporting arm and the accessibility of parts within the interior thereof.

Turning now to Figures XVI to XVIII, there is disclosed a lower unit C of the flat bed type adapted to be combined with the same upper unit A as is disclosed in Figure XV and the earlier views. Preferably, the unit C is completely enclosed by an oil-tight frame or casing 170, having a top plate 171 secured thereto by screws or the like, such as indicated at 172 in Figure XVI. The cover plate, however, extends only from the forward end of the machine back to a portion 173 of the frame (Figures XVI and XVIII), which rises to the top of the base unit at this point. The rear portion of the unit is provided with a large opening at the top, the surrounding wall of which is adapted to receive the standard of the upper unit A. Thus, a chamber 174 in open communication with the interior of the standard 6 is provided. Within the chamber 174 a spur gear 175 is mounted upon a shaft 176 journaled in a bearing 177 carried by the end wall of the frame 170. The forward end of this shaft is connected with a supplemental shaft 178 suitably journaled in the frame and forming, in effect, an extension of shaft 176.

Gear 175 is secured to the shaft 176 by set screws 179 passing through the hub of the gear. It is suitably positioned to mesh with the gear 73 of the upper unit when the units A and C are properly assembled. At this time the bottom of the standard 6 rests upon the upper edges of the series of ears, 180 and 181, extending rearwardly from the portion 173 of the frame. A gasket 183 is provided between the bottom of the standard 6 and the surfaces of the base member C upon which the standard rests. Screws or bolts 184, directed upwardly through openings in the ears 180 and 181, and through passages 185 in the side walls of the frame, serve to secure the two units together. As in the case of the feed-off-the-arm machine, the connection between the upper and lower units is effected entirely by means of the screws or bolts 184, the operating connections between the two units being automatically coupled through the engagement of the gears 73 and 175 as the two frames are secured together.

The complementary stitch forming mechanism and the work feeding devices within the unit C may be of any suitable construction. That disclosed in the Christensen et al. Patent No. 2,128,-120, granted August 23, 1938, may be employed. In general, it may include a series of loopers 186, three being shown in Figure XVI, mounted on a carrier 187 adapted to be rocked through connections including a pitman 188, an arm 189 and a rock shaft 190, the latter being rocked by means of an eccentric 191 on the shaft 176 acting through connections including a pitman 192 and an arm 193.

A feed dog 194 (Figure XVIII) is carried by a feed bar 195 (Figure XVII) and receives a four-motion movement through suitable connections from the shaft 176. These connections may be of the type disclosed in said Christensen et al. patent. As illustrated, the feed bar 195 may be pivotally carried at the upper end of a yoke 196, whose lower end is secured to a rock shaft 197 operated by an eccentric or crank 198, on the shaft 176, through a link 199. An up-and-down movement is imparted to the free end of the feed bar, which carries the feed dog, by another eccentric or crank, not shown, carried by the

shaft 178. As the feed dog is raised, it is passed through the openings in a throat plate 200 carried by the top plate 171 and forces the work against the under side of the presser foot 52.

5 Other suitable devices may be mounted in the frame 170 to meet the particular requirements of the machine. Thread tensioning devices may be so mounted, if desired, and take-up mechanism for the loops of the looper threads may be

10 operated by means on the shaft 178.

Adjacent the gear 175 there is secured to the shaft 176 a disc 201, of relatively large diameter, the lower portion of which is immersed in the lubricant carried housing. Rotation of this disc causes the lubricant to be thrown through the opening at the top of the base unit into the connected standard 6 of the upper unit. This insures adequate lubrication of all of the driving and driven parts within the standard and the 15 aligned portion of the base unit. The devices at the forward end of the base unit are effectively lubricated by the splash action of the various moving parts which dip into the oil.

While the invention has been described in some 20 detail, with reference to a specific embodiment thereof, including an upper unit having a standard and overhanging arm, capable of interchangeable application to either a feed-off-the-arm base unit or a flat bed base unit, it will be understood 25 that numerous changes may be made in the form and arrangement of the various parts without departing from the principles and scope of the invention. Various features of the invention may, 30 at times, be used advantageously without association with other features or devices disclosed herein. The terms and expressions employed in 35 the foregoing have been used as terms of description and not of limitation.

What I claim is:

- 40 1. In a sewing machine a base member having a work support, a vertically disposed standard detachably connected with said base member, a horizontally disposed overhanging arm extending laterally from said standard adjacent its upper end and carrying a needle head above said work support, said standard and said base member having aligned openings therein adapted to be brought into registry upon assembly of said standard and base member, cooperating stitch forming devices in said needle head and in said work support, means including a pair of parallel shafts in said arm and base member, respectively, for synchronously driving said cooperating stitch forming devices, and driving connections 45 between said shafts extending through said aligned openings and adapted to be automatically connected and disconnected upon the assembly and disassembly of said standard and base member, said driving connections forming the sole 50 operating connections between the parts carried by said base member and by said standard and overhanging arm.
- 55 2. In a sewing machine a base member having a work support, a vertically disposed standard detachably connected with said base member, a horizontally disposed overhanging arm extending laterally from said standard adjacent its upper end and carrying a needle head above said work support, said standard and said base member having aligned openings therein adapted to be brought into registry upon assembly of said standard and base member, cooperating stitch forming devices in said needle head and in said work support, means including a pair of parallel 60 shafts in said arm and base member, respec-

tively, for synchronously driving said cooperating stitch forming devices, and driving connections between said shafts extending through said alined openings and adapted to be automatically connected and disconnected upon the assembly and disassembly of said standard and base member, said driving connections including a pair of gears adapted to be meshed and unmeshed upon said assembly and disassembly of the standard and base member, said gears forming the sole operating connections between the parts carried by said base member and by said standard and overhanging arm.

3. In a sewing machine a base member having a work support, a vertically disposed standard detachably connected with said base member, a horizontally disposed overhanging arm extending laterally from said standard adjacent its upper end and carrying a needle head above said work support, said standard and said base member having alined openings therein adapted to be brought into registry upon assembly of said standard and base member, cooperating stitch forming devices in said needle head and in said work support, means including a pair of parallel shafts in said arm and base member, respectively, for synchronously driving said cooperating stitch forming devices, and driving connections between said shafts extending through said alined openings and adapted to be automatically connected and disconnected upon the assembly and disassembly of said standard and base member, said driving connections including a pair of gears

adapted to be meshed and unmeshed substantially in the plane of separation between said standard and base member upon said assembly and disassembly of the standard and base member, said gears forming the sole operating connections between the parts carried by said base member and by said standard and overhanging arm.

4. In a sewing machine a base member having an angled laterally extending work supporting arm, a vertically disposed standard detachably connected with said base member, a horizontally disposed overhanging arm extending laterally from said standard adjacent its upper end and carrying a needle head above said work supporting arm, said standard and said base member having alined openings therein adapted to be brought into registry upon assembly of said standard and base member, cooperating stitch forming devices in said needle head and in said work support, means including a pair of parallel shafts in said arm and base member, respectively, for synchronously driving said cooperating stitch forming devices, and driving connections between said shafts extending through said alined openings and adapted to be automatically connected and disconnected upon the assembly and disassembly of said standard and base members, said driving connections forming the sole operating connections between the parts carried by said base member and by said standard and overhanging arm.

NORMAN V. CHRISTENSEN.
